UNITED STATES PATENT OFFICE.

HERBERT SEVERANCE, OF SAC AND FOX AGENCY, OKLAHOMA TERRITORY.

DESIGN FOR A CUSHION-SPRING FOR CARRIAGE-TOP BOWS.

SPECIFICATION forming part of Design No. 33,473, dated October 30, 1900.

Application filed October 4, 1900. Serial No. 32,055. Term of patent 7 years.

To all whom it may concern:

Be it known that I, HERBERT SEVERANCE, a citizen of the United States, residing at Sac and Fox Agency, in the county of Lincoln and Territory of Oklahoma, have invented and produced a certain new and original Design for Cushion-Springs for Carriage-Top Bows; and I do declare the following to be a full, clear, and exact description of the invention, such as will enable others skilled in the art to which it appertains to make and use the same.

The invention relates to a new and original design for a cushion-spring for carriage-top bows; and it consists of a design of the shape and configuration shown in the accompanying drawings, in which—

Figure 1 is a side elevation. Fig. 2 is a top plan view, and Fig. 3 is an end view.

The leading features of the design comprise the parallel upwardly-inclined sides 1 and 2, the end pieces 3, the coils 4 and 5, arranged intermediate the ends of the sides 1 and 2, and loops 6 and 7, located in a plane below the coils and below the parallel sides. 20

What I claim is—

The design for a cushion-spring for carriage-top bows, as herein shown and described. 25

In testimony whereof I have hereunto set my hand in presence of two subscribing witnesses.

HERBERT SEVERANCE.
